UNITED STATES PATENT OFFICE.

JOSE SUAREZ, JR., OF TAMPA, FLORIDA.

DESIGN FOR A BOTTLE.

Application filed September 15, 1927. Serial No. 23,424. Term of patent 3½ years.

To all whom it may concern:

Be it known that I, JOSE SUAREZ, Jr., a citizen of the United States, residing at Tampa, Florida, have invented a new, original, and ornamental Design for Bottles, of which the following is a specification, drawings, forming a part thereof.

I claim:

The ornamental design for a bottle, as shown.

In testimony whereof I affix my signature.

JOSE SUAREZ, JR.
